(57) **CLAIM**

The ornamental design for a “door lock escutcheon”, as shown and described.

DESCRIPTION

FIG. 1 is a left front bottom perspective view of the “door lock escutcheon” design according to my invention;

FIG. 2 is a right front top perspective view of the “door lock escutcheon” shown in FIG. 1;

FIG. 3 is a front elevational view of the “door lock escutcheon” shown in FIG. 1;

FIG. 4 is a left side elevational view of the “door lock escutcheon” shown in FIG. 1;

FIG. 5 is a right side elevational view of the “door lock escutcheon” shown in FIG. 1;

FIG. 6 is a bottom elevational view of the “door lock escutcheon” shown in FIG. 1; and,

FIG. 7 is a top elevational view of the “door lock escutcheon” shown in FIG. 1.

The rear view of the “door lock escutcheon” is not included and forms no part of the design.
